[57] CLAIM

The ornamental design for a handgrip for snow tools, as shown.

DESCRIPTION

FIG. 1 is a perspective view of a handgrip for snow tools showing our new design;

FIG. 2 is a front view thereof;

FIG. 3 is a left side view thereof, the right side view being a mirror image and symmetrical thereto;

FIG. 4 is a back view thereof;

FIG. 5 is a bottom view thereof; and,

FIG. 6 is a top view thereof.

The broken line showing of a shovel blade and handle shaft is for illustrative purposes only and forms no part of the claimed design.
